HOIST ATTACHMENT

Harold Stephen Mulhollen, Los Angeles, Calif.

Application March 24, 1934, Serial No. 717,208

8 Claims. (Cl. 254—89)

This invention relates to an attachment for a hoist of a character used in elevating automobiles for making accessible the under part for greasing and servicing. Such hoists commonly comprise a frame for engagement with the underpart of the automobile so as to be clear of the wheels together with some mechanism to raise the frame, as for illustration a hydraulic jack. With the advent of independently sprung wheels of various constructions and in some cases elimination of an axle extending across the automobile frame between wheels, the problem has arisen of engaging the automobile so as to allow clearance of the particular spring mechanisms and steering mechanisms, so that the latter will not be damaged.

The present invention has for its object the provision of a hoist attachment whereby the automobile may be supported on a hoist under variable conditions of clearance and comprehends a cross plate together with hoist blocks which may be placed on the cross plate adjusted as to position longitudinally thereon and turned to present different heights of the car engaging surface for supporting the car. In addition to the broader objects of this invention there are certain details of structure contributing to ease of manipulation by the operator, simplicity, strength and economy of manufacture.

These objects are accomplished by the embodiment of my invention illustrated in the accompanying drawing, in which:

Fig. 1 is a perspective view of a fragment of a hoist with my attachment shown in position thereon; Fig. 2 is a fragmentary front elevational view of a hoist with the attachment supporting an axle which may have independently sprung wheels, not shown, the hoist blocks being in high position; Fig. 3 is a fragmentary front elevational view of a hoist with the blocks in low position supporting an axle of a conventional type; and Fig. 4 is a transverse section through a block.

A conventional type of hoist is shown comprising a hydraulic plunger 5. Secured to the head of plunger 5 is a cross plate 6 to which parallel lift beams 7 are secured. The spacing of beams 7 is such that a car may be driven over the hoist frame and the beams will lie within the space between opposite wheels. A base plate 8 spans the beams 7 and overhangs the latter.

The particular base plate shown has curbs 9 preferably welded thereto, these curbs having interruptions on opposite sides adjacent the center for convenience of access to parts and clearance of parts in moving a car into position

thereover. A hand hole 10 is also provided for access to parts of the car. The plate is slidably held on the beams by guide blocks 11 provided with lips hooking under the lift beams. Thus, the base plate may be adjustably positioned along the beams.

The present inventive feature resides in hoist blocks 12 which are unattached to the base plate, but rest thereon. The hoist blocks are identical in construction and are in transverse sections of T shape. They may be made of cast metal, such as cast iron, from rolled metal stock or otherwise as found convenient. The particular blocks illustrated herein are designed to be made of cast iron. The body is of T shape having a recess at its outer marginal edge as indicated by 15 to provide curb lugs 16. The cross arm 17 is likewise recessed at opposite edges as indicated by 18 to provide curb lugs 19. The distance between a bottom wall of a recess 18 and the base line formed between the oppositely disposed corners of the block is less than the distance between the marginal edge of recess 15 and the base line formed between its opposite corners. Although I have shown a block with an equal distance between the marginal edge of each recess 18 and the base line formed by the opposite curb lugs, it is apparent that these distances may be made different. As the particular blocks shown may be accommodated to all the cars now in common use, I have not shown three different distances or heights.

There are now in use some cars having straight axles and some having curved axles with steering knuckles high enough above the axle to permit use of the hoist without the hoist blocks 12. There are other types of cars having axles and steering knuckles so disposed that in raising the car a high clearance above the base plate is required. Blocks providing such clearance, if fixed to the plate, may be too high for the car to be moved into position over the base plate. With my blocks, the car can be moved to position and the blocks then placed in proper position. There are certain cars with independently sprung wheels which require high support above the cross plate. Such high support is secured by disposing blocks 12 in upright position as shown in Fig. 2. The curbs 9 prevent the blocks 12 from slipping transversely of the base plate, the blocks being of such dimensions as to fit between curbs 9. The curb lugs 16 embrace the sides of the axle or parts of the running gear associated with the wheel springing mechanism and prevent slippage of the car from the blocks 12.

In the event, a low support is desired the blocks 12 may be laid on their sides as shown in Fig. 3. The curb lugs 19 prevent slippage of the car. It is obvious that the arms 17 of the blocks may 5 be disposed to face inwardly or outwardly so as to best provide clearance for depending parts of the car.

The particular blocks shown are provided with 10 ribs 20 for purposes of strength, but these are not essential to the invention, being merely mechanical expedients resorted to because the blocks shown are designed to be made of cast iron. It is essential however, that the blocks have three 15 supporting sides, any one of which may be used to obtain variation in supporting heights.

What I claim is:—

1. In a hoist for vehicles, the combination of a cross base plate for registration with a wheel axis and supporting blocks; each supporting block 20 having three sides for selective use as bases to rest on said plate, three triangularly disposed edges forming car contact walls, the distance between a car contact wall and its oppositely disposed side being different from the distance 25 between another car contact wall and its oppositely disposed side.
2. In a hoist for vehicles, the combination of a cross-base plate for registration with a wheel axis and supporting blocks; each supporting block 30 having three sides for selective use as bases to rest on said plate, three triangularly disposed corners on said block, the edges forming said corners being recessed to provide curb lugs at their ends, the distance between the bottom wall of a recess at a corner and the base line between the other corners of said 35 block being different from the distance between the bottom wall of another recess and the base line between its oppositely disposed corners.
3. In a hoist for vehicles, the combination of a cross-base plate for registration with a wheel axis and supporting block; each supporting block 40 having three corners for selective two point support with relation to said corners for resting on said plate, the edges forming said corners being recessed to provide curb lugs at their ends, the distance between the bottom wall of a recess at a corner and the base line between the other corners of said 45 block being different from the distance between the bottom wall of another recess and the base line between its oppositely disposed corners.
4. In a hoist for vehicles, the combination of a cross-base plate for registration with a wheel axis and supporting blocks, said plate having longitudinally extending edge curbs, each block having three sides for selective use as bases to rest 50

on said plate between curbs, the edges of said block forming car contact walls, the distance between a car contact wall and its oppositely disposed side being different from the distance between another car contact wall and its oppositely disposed side. 80

5. In a hoist for vehicles, the combination of a cross base plate for registration with a wheel axis and supporting blocks, said plate having longitudinally extending edge curbs; each supporting block having three sides for selective use as bases to rest on said plate between curbs, three triangularly disposed corners on said block the edges forming said corners being recessed to provide curb lugs at their ends, the distance 90 between the bottom wall of a recess and its oppositely disposed side being different from the distance between the bottom wall of another recess and its oppositely disposed side. 95

6. In a hoist for vehicles, the combination of a cross base plate for registration with a wheel axis and supporting blocks, said plate having longitudinally extending edge curbs; each supporting block having three corners for selective two point support with relation to said corners, 100 said blocks resting on said plate between curbs, the edges forming said corners being recessed to provide curb lugs at their ends, the distance between the bottom wall of a recess at a corner and the base line between the other corners of said 105 block being different from the distance between the bottom wall of another recess and the base line between its oppositely disposed corners.

7. In a hoist for vehicles, the combination of a cross base plate for registration with a wheel axis and supporting blocks; each supporting block being multi-sided for selective use of the sides as bases to rest on said plate, car contact walls opposite said bases, the distance between a car contact wall and its oppositely disposed base 110 being different from the distance between another contact wall and its oppositely disposed base. 115

8. In a hoist for vehicles, the combination of a cross base plate for registration with a wheel axis and supporting blocks; each supporting block being multi-sided for selective use of the sides as bases to rest on said plate, car contact walls opposite said bases, said walls being recessed to provide curb ends, the distance between the bottom 120 wall of a recess and its oppositely disposed base being different from the distance between the bottom wall of another recess and its oppositely disposed base. 125
